C. C. FARMER

CONDUCTOR'S VALVE DEVICE

Filed Oct. 15, 1923

INVENTOR
CLYDE C. FARMER
BY *Wm. M. Oddy*
ATTORNEY

UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

CONDUCTOR'S VALVE DEVICE.

Application filed October 15, 1923. Serial No. 668,576.

To all whom it may concern:

Be it known that I, CLYDE C. FARMER, a citizen of the United States, residing at Pittsburgh, in the county of Allegheny and State of Pennsylvania, have invented new and useful Improvements in Conductors' Valve Devices, of which the following is a specification.

This invention relates to devices employed on a train in backing up for sounding a warning signal and for effecting an application of the brakes when desired.

The principal object of my invention is to provide an improved device of the above character having an operating handle by which a warning signal may be sounded or the brakes applied at will without removing the hand from the operating handle.

In the accompanying drawing; Fig. 1 is a section on the line 1—1 of Fig. 2, showing a construction embodying my invention; Fig. 2 a section on the line 2—2 of Fig. 1; and Fig. 3 an elevational view, showing the combined signal and brake applying device hooked over the platform rail of a car.

As shown in the drawing, the device may comprise a casing 1 having a valve chamber 2 connected to the usual back-up hose 3 which in turn is connected to the usual automatic train brake pipe. In valve chamber 2 there is mounted a poppet valve 4 having a stem 5, the outer end of which engages a lever 6, pivotally mounted on the casing 1.

35 Rotatably mounted on a horizontally projecting portion 7 of casing 1 is a cam or eccentric 8 which is provided with an operating handle 9, and the peripheral face of the cam 8 is adapted to engage the upper face of the lever 6, when the handle 9 is operated. Mounted in a valve chamber 10 of the portion 7 is a poppet valve 11 having a projecting stem 12, the outer end of which is engageable by one end of a lever 13.

40 Said lever 13 is pivotally mounted in the hollow of the handle 9 and is provided at its outer end with a push button 14, which projects through an opening in the handle 9, so that said button may be operated with the hand that grasps the handle.

45 When valve 11 is lifted from its seat, communication is established for supplying fluid under pressure from valve chamber 2

through passages 15 and 16 to a suitable whistle 17. In Fig. 3, the combined signal and brake applying device is shown with the usual hook 18 for applying the same to the platform rail 19 of the car.

55 In operation, the signal may be sounded by operating the push button 14 with the hand which grasps the handle 9, so that the valve 11 is unseated to supply fluid to the whistle 17. If it is desired to apply the brakes, the handle 9 is rotated toward the left from the position shown in Fig. 2, and thereby the cam 8 is rotated, so that the lever 6 is depressed and the stem 5 is then operated by said lever to unseat the valve 4. Fluid is thereupon vented from chamber 2 60 and the automatic brake pipe to exhaust port 20. The brake pipe pressure is thus reduced to effect an application of the brakes in the usual manner.

65 The brakes may be gradually applied to effect a service application or a more rapid discharge of air may be effected to cause an emergency application of the brakes, according to the extent the handle 9 is rotated.

70 When the handle 9 is returned to its normal position, as shown in Fig. 2, the valve 4 closes and the brakes are released by the operation of the usual feed valve on the locomotive to restore the pressure in the brake pipe.

75 It will be evident that the signal may be operated as desired and the brakes applied without removing the hand from the handle 9.

Having now described my invention, what I claim as new and desire to secure by Letters Patent, is:

80 1. A back-up hose attachment comprising a valve for venting fluid to effect an application of the brakes, a valve for operating a signal, a handle for operating one valve, 85 and a lever associated with the handle for operating the other valve.

85 2. The combination with a back-up hose adapted to be connected to the brake pipe, of a valve device connected to said hose and having a valve for venting fluid from the back-up hose to effect an application of the brakes, a signal device, a valve for varying the fluid pressure on said signal device, a handle for operating said brake controlling valve and a push button operated 100

lever associated with the handle for operating said signal controlling valve.

3. The combination with a back-up hose adapted to be connected to the brake pipe, of a valve device connected to said hose and having a valve for venting fluid from the back-up hose to effect an application of the

brakes, a stem for said valve, a pivoted lever engaging said stem, a cam adapted to engage said lever, and a handle for operating said cam to depress said lever.

In testimony whereof I have hereunto set my hand.

CLYDE C. FARMER.
